UNITED STATES PATENT OFFICE.

JOHN E. GARRETTE, OF CINCINNATI, OHIO.

DESIGN FOR A SPRAYING DEVICE.

48,674.

Specification for Design.

Patented Mar. 7, 1916.

Application filed October 11, 1915. Serial No. 55,340. Term of patent 3½ years.

To all whom it may concern:

Be it known that I, JOHN E. GARRETTE, a citizen of the United States, residing at Cincinnati, in the county of Hamilton and State of Ohio, have invented a new, original, and ornamental Design for a Spraying Device, of which the following is a specification, reference being had to the accompanying drawing, forming part thereof.

2 illustrates a plan view. Fig. 3 illustrates a bottom view.

I claim:

The ornamental design for a spraying device as shown.

In witness whereof, I have hereunto subscribed my name this 30th day of September 1915.

JOHN E. GARRETTE.
